UNITED STATES PATENT OFFICE.

ELMER J. GASS AND DAVID W. THURSTON, OF DETROIT, MICHIGAN.

FORM FOR CONCRETE AND THE LIKE.

Application filed May 31, 1922. Serial No. 564,806.

Our invention relates to forms for use with concrete and similar material, and particularly to such forms which may be collapsed or contracted and removed from the concrete after the same has become set. We have devised a form of simple construction and having simple means for contracting it and removing it from the concrete.

Our invention will be better understood by reference to the following description taken in connection with the accompanying drawings forming a part thereof, and in which:

Figure 1 is a longitudinal vertical section 15 of a form embodying our invention;

Figure 2 is a cross section on line II—II of Figure 1;

Figure 3 shows a detail of the means for operating the collapsing means;

Figure 4 is a detail view showing means for holding the cover in place; and

Figure 5 is a partial sectional view of a modified form of the invention.

Referring to the drawings, the device comprises a casing 1 made up of a plurality of wooden members 2. These members are preferably tongued and grooved, seven-eighths by three inches in size and are of any desired length.

The members 2 are covered with galvanized sheet iron of about 26 gage. The form is provided at intervals with supports 3 which preferably take the form of angles. These supports may be placed along the

length of the form at any desired distance apart. Wood members 4 are bolted to the supports 3 by bolts 5. Wood flooring members 2 are attached to the members 4 in any desired manner. The ends of the adjacent

members 4 are cut away so as to provide a space 6 between the ends of these members to allow for contraction, as will be explained later. The supports 3, in the embodiment shown, are bent into circular outline with a

space 7 between the opposed ends. By this arrangement the form is split longitudinally. This split 7 is covered by a metal plate 8 which is held in the position shown in Figure 2 by any suitable means, such as

wires 9, fastened at one end to an eye-bolt 10 in the plate 8, and at their other ends to eye-bolts 11 in the supports 3. The two members 4 adjacent the split in the form or casing, are provided with toggle means

55 which act to hold the form or casing ex-

panded when in position. This toggle arrangement comprises two members 12 and 13 which are hinged together at 14 by a spring hinge. The member 12 is pivotally connected by a pin 15 with one member 4. 60 and the member 13 is likewise pivotally connected by a pin 16 with another member 4. The spring hinge 14 tends at all times to hold the members 12 and 13 in the position shown in Figure 2. Slots are provided 65 to allow the pins 15 and 16 to move when the toggle is broken. By this arrangement, the toggles may be broken without too much tendency towards expansion of the form during the movement of the members 12 and 70 13 to toggle-breaking position.

A link 17 is pivotally connected to the support 3 at 18. A similar link 19 is pivotally connected at 20 with the support 3. The free ends of the links 17 and 19 are 75 connected by a ring 21. This ring has a connection 22 with the toggles 12 and 13. The arrangement of the toggles 12 and 13 is such that when in the position shown in Figure 2 the parts are held in the position 80 shown therein until the toggle is broken.

Extending along the bottom of the form or casing, are spacers 23 and 24 which are held in position by spikes passing through the members 4. These spacers may be made of 85 wood two by six inches and of the required length, to extend between the adjacent supports 3, as shown in Figure 1. A member 26 extends longitudinally of the form or casing and is held in position by the bolts 90 25. Sheaves 27, 28 and 29 are fastened on the member 26, as shown in Figure 1, there being one of these sheaves at each of the supports 3.

The sheaves are held by bearing brackets 95 30 and 31, which are bolted to the member 26, as shown. A cable 32 extends longitudinally of the form or casing, and has attached thereto short cables 33, 34 and 35, connected with corresponding members 21. The cable 100 32 is provided at its outer end with a loop 36 in which may be placed a hook 37 or other suitable means for operating the cable 32 for collapsing or contracting the casing and removing the same from the concrete, as will 105 be explained later.

Figure 5 shows a portion of a form illustrating a modified form of our invention. The essential difference between the form shown in Figure 5 and that heretofore ex- 110

plained, resides in the omission of the members 4 and the substitution of a metal plate 38 for the wood members 2. It will be noted that a slight space 39 is provided around the bolts 40, which hold the plate 38 on the supports 3^a. This is for the purpose of permitting a slight movement of the plate relative to the supports when the form or casing is contracted and removed. The corresponding parts of the device shown in Figure 5 are marked with the same numerals as applied to the other figures, with the exponent "a" added thereto. The operation of the device as shown in Figure 5 is the same as that shown in the other figures, and is as follows:—

If the form is to be used in making a conduit, a ditch, tunnel, or other desired excavation, the excavation is made and the form placed therein. The parts are then moved to the position shown in the drawings and concrete or similar material is poured around the form in the usual way and is allowed to remain until it sets. When it is desired to remove the form from the concrete, suitable power is applied to the cable 32 to draw the same to the left as viewed in Figure 1. The movement of the cable 32 causes a downward movement of the cables 33, 34 and 35, breaking the toggles 12 and 13, and carrying downwardly the free ends of the links 17 and 19. The downward movement of the links 17 and 19 contracts the form throughout its length, thus separating it from the hardened material 41. The power which is applied to the cable 32 also acts to move the form longitudinally out of the molded shape.

Our invention has many advantages. Among which may be mentioned simplicity of construction; simplicity of the means for collapsing or contracting the form simultaneously throughout its length, thus relieving it from the concrete throughout its length; and serving to remove the form from the concrete. By the arrangement of the device shown it may be successively moved to permit the formation of an indefinite length of sewer or other similar structure. Furthermore, this type of form may be collapsed or set up after it has been moved, by means operated from outside the form, thus eliminating the danger incident to men going into the form, as has been necessary heretofore. The very simple provision of the flexible means such as wires 9 for holding the slit cover 8 in place allows the cover to move up as the form is expanded and to move inwardly when the form is collapsed and at the same time keep the cover in proper position over the slit.

While we have shown and described two embodiments of our invention, it will be understood that we are not limited to the exact arrangements shown and described, as many

changes may be made in the details of construction without departing from the spirit of our invention.

We claim—

1. A form for concrete and the like, having a plurality of sets of toggles for holding the form in its expanded position, a set of links for each set of toggles connected to opposite sides of the form and the toggles, and means for operating all of said sets of links to break the toggles and to contract the form throughout its length, substantially as described. 70

2. A form for concrete and the like, a plurality of sets of toggle levers for holding the form in its expanded position, a plurality of pairs of transversely extending links, each link being connected at one end to the form and at the other end to the free end of the other link of that pair, a connection between each pair of toggle levers and the free ends of a pair of links, and common means for moving the free ends of the links of all the pairs to break the toggle levers to contract the form, substantially as described. 80

3. A form for concrete, comprising a contractable casing having an opening extending longitudinally thereof when the casing is expanded, toggle levers extending across the opening and connected to the end portions of the casing on opposite sides of the opening, said toggle levers being substantially parallel when the casing is expanded, links connected to each other and the ends of the casing, an actuating connection between the toggle levers and the links, said links being so arranged that when they are moved away from the toggle levers, the toggle levers will permit the contracting of the casing when the links are swung about said connections, and means for actuating the links, substantially as described. 90

4. A form for concrete, comprising a flexible casing of circular form, there being a longitudinal opening in the casing when the form is expanded, a plurality of sets of toggle levers pivotally connected to the end portions of the casing and extending across the opening between the center of the casing and the opening, a set of links for each set of toggle levers between the toggle levers and the center of the casing, one end of each link of each set being pivoted to one end portion of the casing, the other ends of the links of each set being connected to each other and to a set of the toggle levers, said links being arranged to first break the lock formed by the toggle levers and then contract the casing when the ends of the links are drawn toward the center of the casing, and means for simultaneously drawing the links of each set toward the center of the casing, substantially as described. 100

5. A form for concrete, comprising a flexible casing of circular form, there being a 110

- longitudinal opening in the casing when the form is expanded, a cover for the opening held in position by flexible connecting means connected to the end portions of the casing,
- 5 a plurality of sets of toggle levers pivotally connected to the end portions of the casing and extending across the opening between the center of casing, and the opening, a set of links for each set of toggle levers between
- 10 the toggle levers and the center of the casing, one end of each link of each set being pivoted to one end portion of the casing, the other ends of the links of each set being connected to each other and to a set of the toggle
- 15 levers, said links being arranged to first break the lock formed by the toggle levers and then contract the casing when the ends of the links are drawn toward the center of the casing, and means for simultaneously
- 20 drawing the links of each set toward the center of the casing, substantially as described.

6. A form for concrete and the like, comprising a collapsible casing, and means for

25 normally holding said casing in its expanded operative position, said means being adapted upon the application of force thereto to move said casing to contracted position and to thereafter automatically move it back

30 into its expanded operative position upon the removal of said force therefrom, substantially as described.

7. A form for concrete and the like, comprising a collapsible casing, means for normally holding said casing in its expanded

35 operative position, and means operatively

connected to said holding means whereby to simultaneously contract said casing and remove it from the concrete surrounding the same, said holding means being adapted to automatically return said casing into its expanded operative position upon release of said last mentioned means, substantially as described.

8. A form for the concrete and the like, comprising a collapsible casing, means for normally holding said casing in its expanded operative position, and means including a cable operatively connected to said holding means whereby upon exerting tension upon said cable to simultaneously contract said casing and remove it from the concrete surrounding the same, said holding means being adapted to automatically return said casing into its expanded position upon relaxation of the tension upon said cable, substantially as described.

9. An expansible form for concrete and the like, comprising a longitudinally split casing, a cover plate outside the casing and resting thereon, extending along the split in the casing, flexible connectors connecting the cover plate with the casing at opposite sides of the split and serving to hold the cover plate in central position when the casing is expanded, and means for expanding and contracting the casing.

In testimony whereof we have hereunto set our hands.

ELMER J. GASS.
DAVID W. THURSTON.
